UNITED STATES PATENT OFFICE.

OTTO C. L. HIRSCH, OF EVANSTON, ILLINOIS.

COLLAPSIBLE TABLE.

1,194,019.

Specification of Letters Patent.

Patented Aug. 8, 1916.

Application filed October 7, 1915. Serial No. 54,554.

To all whom it may concern:

Be it known that I, OTTO C. L. HIRSCH, a subject of the Emperor of Germany, residing at Evanston, in the county of Cook and 5 State of Illinois, have invented a certain new and useful Improvement in Collapsible Tables, of which the following is a full, clear, concise, and exact description, reference being had to the accompanying drawing, forming 10 a part of this specification.

My invention relates to collapsible tables, and has for its object the provision of a structure which when in its distended condition may serve the purposes of a long table, 15 but which structure is of such a character that when the various parts are taken apart and collapsed, all of them may occupy a very small space, and in fact may in one form of the invention be placed within a carrying 20 case, and which carrying case under such conditions may then also be utilized as part of the table structure.

My invention for instance is applicable for use by workmen such as paper hangers 25 who use a table which is carried from one house to another as it is required in the work.

In the particular form of the invention in which a carrying case incloses all of the parts and itself forms a portion of the table 30 structure, I may say that there is also sufficient room in this carrying case to permit of placing other articles in the carrying case so as to accommodate probably nearly the whole kit of the workman. I will explain 35 this particular form which my invention may take more in detail by referring to the accompanying drawings, in which—

Figure 1 is a side view of the table in its distended condition; Fig. 2 is a portion of 40 the table top in collapsed form; Fig. 3 is one of the side frames or stringers of the table in section on line *a—a* of Fig. 1; Fig. 4 is a sectional view of one of the braces for holding the legs on line *b—b* of Fig. 1; Fig. 5 is a top view partly in section of my im- 45 proved table with the collapsible portion of the top removed along lines *c—c* of Fig. 1; Fig. 6 is a sectional view on line *d—d* of Fig. 5; Fig. 7 is a sectional view on line *e—e* of Fig. 1; Fig. 8 shows a carrying case formed 50 of part of the table structure; Fig. 9 is a plan view of the carrying case open with all of the parts in position, and Fig. 10 is a sectional view on line *f* of Fig. 9.

My improved device as specifically shown herein includes a carrying case 1 such as shown in Fig. 8 when in its closed position,

which carrying case has the two halves 2 and 3. This carrying case may have a suitable handle 4, and has hinge plates 5 and 6 60 which are, when the case is in the condition of Figs. 8, 9 and 10 held together by pintles 7. This carrying case which is shown in its open position in Figs. 9 and 10 contains all of the various parts necessary to make the 65 table as shown in Fig. 1. The section 2 has extensible legs 8 and 9 and the section 3 has extensible legs 10 and 11. These legs in general are as shown in section in Fig. 7 and include a hinged sleeve member 12 hinged so 70 that it may be collapsed into the position shown in Figs. 9 and 10, or bent outwardly as shown in Figs. 1, 6 and 7. This sleeve member 12 carries the leg proper 13 which is slideable in the sleeve member so as to be 75 collapsible, a spring controlled pin 14 holding the leg member 13 in either of its distended positions. A clasp 15 pivotally mounted in the sleeve structure 12 may be slipped around into position as shown in 80 Figs. 1 to 7 to hold the legs in their proper position when they have been moved outwardly. The two sections 2 and 3 of the carrying case when separated may be stood upon the legs as shown more clearly in Figs. 85 1, 5 and 6 to form a part of the table.

In order to complete the table structure I employ two side frames or stringers 16, 17. The side frame 16 is hinged together as 90 shown at 18 and has hinge elements 19 and 20 by means of which it can be fastened to the case sections 2 and 3 at 21 and 22 as readily apparent by means of pintles. This side frame 16 also has collapsible arms 23 mounted thereon, which may serve to hold 95 the rule or straight edge or other operating element when the table is in use. This side frame 16 further co-operates with braces 24, 24, which braces are held in place on said side frame by means of pins 25. Latches 26 100 hold the two portions of the brace in a straight line when said catch or clasp is actuated. These braces 16 then co-operate with the legs 8 and 10 as shown more clearly in Fig. 5. This side frame 16 also has a 105 sliding bolt 27 to hold it in its alined position as is readily understood. The side frame 17 is similarly constructed, having also a bolt 28 to hold it in its straight position, but carries pivotally attached thereto the braces 29, 29. These braces are adapted 110 to co-operate with the legs 9, and 11, these braces likewise being collapsible by being pivotally connected by the pin 30 and held

in their straight position by the movable pin 31.

The structure thus far described when assembled presents approximately the appearance shown in Fig. 5. Between the two sections 2 and 3 and on top of the side frames 16 and 17 a collapsible top 32 is placed, which collapsible top is shown in its collapsed position in Fig. 2. The collapsed top may be held on top of the side frames in any suitable manner, no special holding means being here illustrated as it is not thought necessary.

I have thus described a complete table which can be folded into very small compass.

From what has been described it will be readily clear to those skilled in the art, and it will also be clear that many modifications can be made without departing from the spirit of my invention.

What I therefore claim as new and desire to secure by Letters Patent is:

1. A collapsible, portable table structure of the character described having two top sections adapted to form the end portions of the table top, legs for said top sections, collapsible side frames detachably uniting said top sections, and a collapsible top on top of said side frames between said top sections and supported by said side frames.

2. A collapsible, portable table structure of the character described having two top sections adapted to form the end portions of the table top, said top sections being both substantially alike and each forming one-half of a carrying case, legs for said top sections, collapsible side frames detachably uniting said top sections, and a collapsible top on top of said side frames between said top sections and supported by said side frames.

3. A collapsible, portable table structure of the character described having two top sections adapted to form the end portions of the table top, said top sections being both substantially alike and each forming one-half of a carrying case, means for detachably holding said sections together when said table structure is collapsed, said top sections serving as a container for the remaining elements of said table structure, legs for said top sections, collapsible side frames detachably uniting said top sections, legs for said top sections, collapsible side frames between said top sections and supported by said side frames.

4. A collapsible, portable table structure of the character described having two top sections adapted to form the end portions of the table top, said top sections being both substantially alike and each forming one-half of a carrying case, means for detach-

ably holding said sections together when said table structure is collapsed, said top sections serving as a container for the remaining elements of said table structure, collapsible legs for said top sections, collapsible side frames detachably uniting said top sections, and a collapsible top on top of said side frames between said top sections and supported by said side frames.

5. A collapsible, portable table structure of the character described having two top sections adapted to form the end portions of the table top, said top sections being both substantially alike and each forming one-half of a carrying case, means for detachably holding said sections together when said table structure is collapsed, said top sections serving as a container for the remaining elements of said table structure, collapsible legs for said top sections, said legs being hinged to said top sections, side frames detachably uniting said top sections, and a collapsible top on top of said side frames between said top sections.

6. A collapsible, portable table structure of the character described having two top sections adapted to form the end portions of the table top, said top sections being both substantially alike and each forming one-half of a carrying case, means for detachably holding said sections together when said table structure is collapsed, said top sections serving as a container for the remaining elements of said table structure, legs for said top sections, side frames detachably uniting said top sections, a collapsible top on top of said side frames between said top sections, and detachable braces extending from said side frames to said legs.

7. A collapsible, portable table structure of the character described having two top sections adapted to form the end portions of the table top, said top sections being both substantially alike and each forming one-half of a carrying case, means for detachably holding said sections together when said table structure is collapsed, said top sections serving as a container for the remaining elements of said table structure, legs for said top sections, side frames detachably uniting said top sections, a collapsible top on top of said side frames between said top sections, detachable braces extending from said side frames to said legs, and collapsible supporting arms extending horizontally from one of said side frames.

In witness whereof, I hereunto subscribe my name this 4th day of October, A. D. 1915.

OTTO C. L. HIRSCH.
